UNITED STATES PATENT OFFICE.

DONALD F. FRASER, OF LANCASTER, PENNSYLVANIA, ASSIGNOR TO ARMSTRONG CORK COMPANY, OF LANCASTER, PENNSYLVANIA, A CORPORATION OF PENNSYLVANIA.

PRINTING-BLOCK GAUGE TABLE.

Application filed April 4, 1925. Serial No. 20,747.

To all whom it may concern:

Be it known that I, DONALD F. FRASER, a citizen of the United States, residing at Lancaster, county of Lancaster, and State 5 of Pennsylvania, have invented a new and useful Improvement in Printing-Block Gauge Tables, of which the following is a full, clear, and exact description.

The present invention relates to printing 10 blocks such as are employed in the making of printed linoleum and similar floor covering and more particularly to means for truing or leveling the printing surfaces thereof.

In the making of printed linoleum the 15 goods is run under a series of vertically reciprocable printing blocks each adapted to print a portion of the complete pattern in the desired color. Paint is applied to the printing surfaces of these blocks and they 20 are moved into contact with the goods in timed relation to the travel thereof under the blocks so as to match up the partial patterns to form the complete pattern. In order that these printing blocks may properly 25 perform their functions, it is not only necessary that all points on the printing surface of a block be located in the same plane so that when the printing surface is brought into contact with the goods all said points 30 will contact with the goods, but that the printing surfaces of the several blocks be relatively adjusted so that their partial patterns will match up perfectly on the goods to form the complete pattern.

The present invention provides a gauge 35 table assembly for facilitating these adjustments. The various blocks for forming a complete pattern are successively supported in this table assembly and their printing 40 surfaces leveled up with respect to a gauging surface, which is the surface of the table, and the printing surfaces adjusted laterally and longitudinally so that their partial patterns will match up perfectly to form the 45 complete pattern. The table assembly has a pattern screen associated therewith and adapted to be placed in operative relation to the printing surface of each block to enable such surface to be laterally and longitudinally adjusted in order to cause its partial 50 pattern to match up with the partial patterns of the printing surface of the other blocks in a manner to be hereinafter described in detail. When the printing blocks

have had their printing surfaces leveled up 55 and adjusted, they require only slight adjustments when placed in the printing machine in order to cause their partial patterns to match up on the goods.

A preferred embodiment of the invention 60 is illustrated in the accompanying drawings, wherein:

Figure 1 is a front elevation of the table assembly, showing a printing block supported therein and showing the pattern 65 screen in inoperative position;

Figure 2 is an end elevation of the structure shown in Figure 1, looking from the right;

Figure 3 is a fragmentary longitudinal 70 vertical section of the structure;

Figure 4 is a sectional plan view, partly broken away, of the upper portion of the printing block and the rotatable support therefor shown in Figure 3, the section being taken on the line IV—IV of Figure 3;

Figure 5 is a transverse sectional view, on a larger scale, of the printing block;

Figure 6 is a plan view, and

Figure 7 is a side elevation, partly in section, of a supporting bracket for one end 80 of the printing block;

Figure 8 is a perspective view of one of the shims for leveling up the printing surface of the block;

Figure 9 is a detail sectional view through one end of the printing block and the supporting and adjusting means associated with one end thereof;

Figure 10 is a view looking at one end 90 of the printing block, the supporting and adjusting bracket being shown in dotted outline and in section;

Figure 11 is a perspective view of one of the wedges for vertically adjusting the rotatable support at one end of the table;

Figure 12 is a perspective view of the bearing bracket connected to one end of the printing block; and

Figure 13 is a perspective view of the 100 bearing block connected to the other end of the printing block.

Referring to the illustrated embodiment of the invention, 2 designates a table the plain horizontal upper surface of which 105 constitutes a gauging surface or a surface of reference. This table is supported at a convenient location by legs 3. At the op-

posite ends of the table are brackets 4 and 5 each of which provides a half bearing for a rotor 6. The other half of each bearing is provided by a removable cap 7, these 5 caps being bolted to the brackets 4 and 5. Each rotor has a sprocket 8 mounted thereon engaged by a sprocket chain 9 which also engages a sprocket 10 on a hub 11. The hubs 11 are formed integral with handles 10 12 mounted on the opposite ends of a shaft 13 extending under the table 2. With this construction both rotors are adapted to be turned simultaneously by means of either handle 12. Each sprocket chain 9 is engaged by a roller 9^a carried by an adjustable bracket 9^b, whereby the slack in the sprocket chain can be taken up.

The rotors 6 are adapted to rotatably support a printing block 14 in order to 20 facilitate the various adjustments referred to above. A printing block such as illustrated comprises I-beams 15 which are held in spaced relation by brackets 16 secured thereto by bolts 17. Connected to 25 these brackets are braces 18 which extend longitudinally between the I-beams and brace the entire block structure. Secured to the base flanges of the I-beams 15 by clamps 19 and clamping screws 20 are trans- 30 versely extending castings 21. The castings 21 hold the printing element 22, said printing element being secured thereto by screws 23 passing through slots 24 in the castings and cooperating with lag screws 25 35 in the printing element. The printing element is a laminated structure formed of a plurality of layers of wood, the lowermost one having the printing characters or types 26 formed on its surface.

40 Fastened to and extending between the I-beams 15 at each end of the block is a bracket 27. Each of these brackets is secured to the I-beams by bolts 28 and 29, the bolts 28 extending through the webs 45 of the brackets and the webs of both I-beams, and the bolts 29 extending through flanges at the ends of the webs of the brackets and through the webs of the I-beams. Each bracket has a horizontal flange 30 50 projecting outwardly from the lower edge of its web portion, this horizontal flange having downwardly extending arms 31 at its ends. A bearing bracket 32 or 32^a, shown in Figures 12 and 13, is secured to the lower face of each horizontal flange 30 55 by a pair of pins 33, screw-threaded at their opposite ends, screwed into the bearing bracket and extending through slots 34 in the flange 30 and having nuts 35 and washers 36 cooperating with their screw-threaded upper ends. Shims 37 may, if desired, be interposed between the washers 36 and the upper surfaces of the flanges 30. Set screws 38 extend through the arms 60 65 31 and engage the sides of the bearing brackets 32 and 32^a, whereby the printing block can be laterally adjusted with respect to the bearing brackets by loosening the nuts 35 and screwing in one of the set screws 38 at the end of the printing block and 70 backing off the other set screws.

Each rotor 6 has a central opening 39 and a horizontal flange 40 projecting inwardly from said opening. Mounted upon said flange and secured thereto by a bolt 41 is 75 a supporting bracket 42, shown in Figures 6 and 7, having a yoke portion 43 the arms of which are adapted to straddle the sides of a depending portion 44 of the bracket 32 or the bracket 32^a. A pin 45 having 80 tapering ends extends through the arms of the yoke portion 43 and through bearings 46 slidably mounted in openings in the depending portion 44. The ends of the pin 45 are tapered in order to facilitate its 85 insertion and removal from the yoke 43 and the bearings 46. A screw 47 is mounted in the yoke portion 43 of one of the brackets 42 and has an annular groove 48 in its inner end and a wrench engaging portion at its outer end. The bearing block 32 has spaced arms 49 projecting 90 inwardly from the depending portion 44 and these arms have pins 50 projecting from their inner faces and adapted to extend into 95 the annular groove 48 of the screw 47. It will be apparent that with this construction the printing block can be adjusted longitudinally while supported in the table assembly. Each of the bearing blocks 32 and 32^a has a pin 51 projecting therefrom for 100 cooperation with a crane hook to facilitate mounting the printing block in the table assembly and removing it therefrom and placing it in the printing machine.

The method of truing up or leveling the printing surface of the printing block will now be described. Each rotor 6 has two diametrically opposite holes 52 therein adapted to receive the tapered end of a pin 53 insertible in an opening in the bearing bracket. This pin has its outer end screw threaded and engaged by a nut 54. It will be seen that by tightening the nut, the removal of the tapered pin is facilitated. The tapered pins are adapted to hold the printing block with its printing surface either facing downwardly and substantially parallel to the surface of the table or facing upwardly for cooperation with the pattern screen, which will be hereinafter described. When the printing block is mounted in the table assembly it is first held with its printing surface facing downwardly. The bearing bracket 4 at one end of the table is supported on cooperating wedges 55 and 56, one of which is shown in Figure 11. The upper wedge 55 has flanges 57 forming a channel to receive the bearing bracket 4. Each wedge is provided with longitudinal slots 115 120 125 130

58 and 59 at its opposite ends through which extend pins 60. These pins extend through the base of the bearing bracket 4 and into openings in a horizontal flange 61 at the 5 end of the table. These pins prevent lateral movement of the bracket while permitting it to be vertically adjusted by means of the wedges 55 and 56. Each of these wedges has a T slot 62 at one end adapted to be engaged by the head of an adjusting screw 63 which extends through a bracket 64 and has a lock nut 65 cooperating therewith. It will be apparent that by turning these 10 screws the wedges may be adjusted in and out in order to raise or lower the bearing bracket 4. When the printing block is placed in the table assembly and held with its printing surface facing downwardly, the printing surface may have one end thereof 15 at a slightly greater or less elevation from the surface of the table 2 than the other end thereof, which can be determined by means of a suitable gauge. If this is the case, this can be remedied by vertically adjusting the bearing bracket 4 in the manner described.

After the printing surface has been adjusted so that its opposite ends are at the same elevation from the surface of the table, 20 then the gauge is employed to determine whether or not all points on the printing surface are at the same elevation from the surface of the table. Naturally some points will be at a greater elevation than other 25 points, but it is absolutely necessary in order that the block may perform its functions properly in printing that all points on the printing surface be in the same plane. In order to bring all points on the surface of 30 the drawing block at the same elevation from the surface of the table 2, shims 66, a preferred form of which is shown in Figure 8, may be inserted between the upper surface of the printing element 22 and the ends 35 of the castings 21. These shims can be inserted by first loosening the screws 23 at the ends of the castings and inserting the shims and then tightening up the screws. It will 40 be seen that by means of these shims all 45 points of the printing surface can be brought into the same plane.

After the printing surface has been leveled in the manner described, the pins 63 are removed from the openings 52 with 55 which they were engaged and the printing block rotated 180° to bring its printing surface facing upwardly. The pins 53 are then inserted in the diametrically opposite 60 openings 52 to hold the block in this position. Pivoted to brackets 67 extending upwardly at one side of the table is a frame 68. This frame is adapted to hold a pattern screen 69, preferably of oil silk. The 65 frame is normally held in the inoperative position shown in Figures 1 and 2 by

weights 70 connected thereto by cables 71 passing over sheaves 72. When the printing surface of the first block of the series of blocks forming a complete pattern is faced upwardly, a thin ink or paint of any desired color is applied to said surface. The pattern screen is then brought down into contact with the printing surface in order that the partial pattern of the printing block may be printed on the pattern screen. 70 Extending upwardly from the opposite side of the table from that at which the frame 68 is pivoted are brackets 73 which have set screws 74 engaged with their upper ends. These set screws form adjustable stops for 75 the frame 68 when the latter is swung downwardly into the dotted line position shown in Figure 2. By adjusting these set screws the pattern screen can be made to contact evenly with the printing surface of the 80 block at all points. Having printed the partial pattern of the first block on the pattern screen, the latter is again moved to inoperative position and then the printing block is removed from the table assembly 85 and may be placed in the printing machine. In order to permit removal of the block it is only necessary to remove the tapered pins 45, which releases the bearing blocks 32 and 32' from the supporting brackets 42. 90

The second printing block of the series is now placed in the table assembly and its printing surface leveled in the manner previously described. The block is then rotated to face its printing surface upwardly 100 and the pattern screen is moved down over the printing surface, as shown in dotted lines in Figure 2. Then by looking through the pattern screen the operator can determine what adjustments are necessary in 105 order to make the partial pattern of the second block match up with the partial pattern of the first block which has been printed on the pattern screen. These adjustments can be made by longitudinally adjusting 110 the printing block by means of the screw 47 and by laterally adjusting it by means of the set screws 38. Ordinarily the set screws 38 will take care of all the lateral adjustments that are necessary, but it will be noted, 115 by reference to Fig. 5, that the printing surface 22 can be also adjusted laterally by loosening the screws 23, since the slots 24 through which these screws extend admit of a slight lateral adjustment of the printing element with respect to the castings 21. After the printing surface of the second block has been adjusted to make it match 120 up with the partial pattern of the first block, the second block can be removed and the third block placed in the table assembly and its printing surface leveled up and adjusted 125 in the same manner as described for the second block. It will be obvious that after the second block has had its printing sur- 130

face adjusted to match up with the partial pattern of the first block, paint of a suitable color can be applied to its surface and its partial pattern also printed on the pattern screen, in order to facilitate the matching up of the partial pattern of the third printing block with the partial patterns of the first and second blocks. This can also be repeated for the third block and each successive block except the last block of the series, it obviously being unnecessary to print the partial pattern of the last block on the pattern screen. However, if the complete pattern only consists of a relatively small number of partial patterns it may not be necessary to print the partial pattern of any of the blocks on the pattern screen except that of the first block.

The printing machine has means engageable with the bearing brackets 32 and 32^a at the ends of the printing blocks similar to the supporting brackets 42. When the blocks have been adjusted in the table assembly and placed in the printing machine no lateral adjustments of the printing blocks are necessary in order to make the partial patterns of the blocks match up perfectly on the goods. Some slight longitudinal adjustments of the blocks may be necessary, but these are easily and quickly made and a relatively small amount of the goods has to be run under the blocks in order to make these adjustments.

While I have illustrated and described a preferred embodiment of my invention, it will be understood that the invention is not limited to its illustrated embodiment, but that it may be otherwise embodied within the scope of the appended claims without departing from the spirit of the invention.

I claim:

1. In means for truing and leveling the printing surfaces of printing blocks, a table having a gauging surface and having means engageable with the opposite ends of a printing block for supporting said block with its printing surface facing and in spaced relation to the surface of said table and substantially parallel therewith, one of said means being adjustable whereby to enable one end of the printing surface of the block to be adjusted to the same distance from the surface of the table as the other end thereof, substantially as described.

2. In means for truing and leveling the printing surfaces of printing blocks, a table having a gauging surface, said table having rotatable means engageable with the opposite ends of a printing block for supporting said block with its printing surface either facing the surface of the table or facing away from said surface, means for holding said block in either of said positions, a pattern screen, means for supporting said pattern screen so that it may be moved into co-

operative relation with the printing surface of the block when said surface is in the latter of said positions, and means at the opposite ends of the table for adjusting the block laterally and longitudinally, substantially as described.

3. In means for truing and leveling the printing surfaces of printing blocks, a table having a horizontal gauging surface, said table having rotatable means engageable with the opposite ends of a printing block for supporting said block above the table with its printing surface either facing downwardly and substantially parallel with the surface of the table or facing upwardly, means for holding said table in either of said positions, a pattern screen, means for supporting said pattern screen so that it may be moved into operative relation with the printing surface of the block when said surface is faced upwardly and to have the partial pattern of said block printed thereon, and means at the opposite ends of the table for adjusting the block laterally and longitudinally, substantially as described.

4. In means for truing and leveling the printing surfaces of printing blocks, a table having a horizontal gauging surface, said table having rotors at its opposite ends engageable with the opposite ends of a printing block for supporting said block above the table with its printing surface either facing downwardly and substantially parallel to the surface of said table or facing upwardly, means engageable with said rotors for holding said table in either of said positions, bearings for said rotors, means for adjusting one of said bearings vertically, a pattern screen, means for supporting said pattern screen so that it may be moved into operative relation with the printing surface of the block when said surface is faced upwardly, and means at the opposite ends of the table for adjusting the block laterally and longitudinally, substantially as described.

5. In means for truing and leveling the printing surfaces of printing blocks, a table having a horizontal gauging surface, said table having rotors engageable with the opposite ends of a printing block for supporting said block above the table with its printing surface either facing downwardly and substantially parallel with the surface of said table or facing upwardly and substantially parallel with the surface of said table, means engageable with said rotors for holding said table in either of said positions, means for simultaneously operating both of said rotors, a pattern screen, means for supporting said pattern screen so that it may be moved into operative relation with the printing surface of the block when said surface is faced upwardly, and means at the opposite ends of the table for adjust-

ing the block laterally and longitudinally, substantially as described.

6. The combination with a series of printing blocks each having bearing brackets attached to its opposite ends, and means for adjusting the block laterally with respect to said bearing brackets, of means for truing and leveling the printing surfaces of said blocks, comprising a table having a horizontal gauging surface, said table having rotatable means engageable with the bearing brackets at the opposite ends of each printing block for supporting said block above the table with its printing surface either

facing downwardly or facing upwardly, 15 means for holding said table in either of said positions, a pattern screen, means for supporting said pattern screen so that it may be moved into operative relation with the printing surface of the block when said 20 surface is faced upwardly, and means engageable with one of said bearing brackets for adjusting the block longitudinally while supported by said rotatable means, substantially as described. 25

In testimony whereof I have hereunto set my hand.

DONALD F. FRASER.
